(57) **CLAIM**

The ornamental design for a pilates bar, as shown and described.

DESCRIPTION

FIG. 1 is a first perspective view of a pilates bar showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 1.

The dash-dot broken lines shown in FIGS. 1, 9, and 10 show the bounds of the detail views and form no part of the claimed design. All other broken lines show portions of the pilates bar that form no part of the claimed design.

1 Claim, 10 Drawing Sheets
